Neil D. Weston,
his ATTORNEY

UNITED STATES PATENT OFFICE

OSCAR A. ROSS, OF NEW YORK, N. Y., ASSIGNOR TO GENERAL RAILWAY SIGNAL COMPANY, OF GATES, NEW YORK, A CORPORATION OF NEW YORK

AUTOMATIC TRAIN CONTROL

Original application filed December 28, 1921, Serial No. 525,508, Divided and this application filed July 16, 1928. Serial No. 293,047.

My invention relates more particularly to apparatus to be applied to such inductive forms of automatic train control, as for example, is disclosed in my prior Patent 5 #1,399,796, dated Sept. 13, 1921, and has for its most prominent object the production of simpler, more economical and rugged devices.

Another object of my invention is to produce an apparatus which will not occupy 10 space other than that ordinarily occupied on the trackway of the railroad.

Another object is to provide for the suitable attachment of the track member to the rails whereby the creeping or other movements of the rails will not interfere with proper functioning of the devices employed.

This application is a division of my prior application Ser. No. 525,508 filed December 28, 1921.

20 Whereas it is obvious that those skilled in the art may make modifications not departing from the spirit of my invention, I have shown my preferred form in the accompanying drawings, in which:

25 Fig. 1, is a part plan, part sectional view of my invention as applied to a trackway;

Fig. 2, is a part plan, part sectional view taken on the line E—E of Fig. 1;

Fig. 3, is a plan view taken on line F—F of 30 Fig. 1;

Fig. 4, is an enlarged plan view of part of the magnetic core of the track element;

Fig. 5, is a section on line G—G of Fig. 4; and

35 Fig. 6, is a section on line H—H of Fig. 4.

Referring in detail to the various figures in which line numerals refer to like references in the several drawings, Z is a track element comprising a magnetic core 1, on which 40 is shown a coil 2, having leads 3—3, clamped to external leads 4—4, by connectors 5—5. External leads 4—4 enter through conduit 6 secured to plate 7 suitably secured to end block 8 of track element Z. Magnet core 1

45 and its coil 2 are, with the exception of core ends 9—9, completely housed by top and bottom plates 10 and 11, side plates 12 and 13, and end blocks 8 and 14, all of which are held together by suitable bolts and screws 15—15.

50 The magnet core 1 and coil 2 are not only lo-

cated and braced by core ends 9—9 passing through the top plate 10, but also by blocks 16—16, and 17—17. All the plates and blocks forming the housing and braces for core 1, are of non-magnetic material.

To facilitate making connections to leads 3—3 of coil 2 a compartment 20, formed by blocks 18—18, 19, and top and bottom plates 10 and 11, is provided. A hole 21 fitted with a cover 22 is also provided through which suitable tools may be inserted for making connections.

Track element Z is preferably designed to take up space usually occupied by a railroad tie and is placed under rails 24—24, the core 65 ends 9—9 pressing firmly against the underside of said rails, but being electrically insulated therefrom by insulation 25—25.

The firm pressure of core ends 9—9 against the bottom of rails 24—24 is obtained through 70 springs 26, seated in yokes 27, which yokes are secured to rails 24—24 by clamps 28—28, said clamps being arranged so that when bolts 29—29 are tightened, the track rails 24, yoke 27, and clamps 28 and 28 become a solid member 75 acting as a saddle on each rail, in which member Z is held through springs 26—26, the upper ends of which impinge on the plates 30, secured to bottom plate 11.

To economically produce the magnetic core 80 1, the laminations are assembled as shown by Figs. 4, 5, and 6, each alternate lamination 32, abutting an end lamination 34, with end laminations 33 abutting laminations 31.

All of the space in member Z, not occupied 85 by essential parts, is filled with insulating compound 60 through apertures 69—69. This does not apply to compartment 20. For the purpose of illustrating the several parts clearly this compound is assumed to be transparent.

In Fig. 4, the laminations are drawn thicker than ordinarily employed in practice so as to clearly indicate their assembly. The lamination 31—32, 33 and 34 are clamped into a 90 unit forming core 1 by plates 73—73 and bolts 74—74, the units of which are electrically insulated in any well known manner to prevent eddy currents as the flux surges through magnet core 1.

I have discovered that due to vibration from passing vehicles the track element Z cannot be rigidly secured to rails 24—24, for if so secured, the creeping and other movements of the rails will soon work it loose, causing poor magnetic contact with the rails. As the track circuit is the well known basis for operating automatic train control or other forms of signalling, it is obvious that magnetic core 1, cannot be welded thereto, as it would cause a short circuit.

What I claim is:—

1. As a container for the track magnet of an inductive train control system for a railway, the combination of top and bottom plates, side plates and end plates with means for rigidly connecting all of the plates together to form a hollow structure containing a track magnet and coil therein, one of said end plates being formed with an orifice and all of the free space of the container being filled with an insulating compound except a cavity adjacent to and connecting with the said orifice, and terminal strips in said cavity.
2. As a track element of an inductive train control system for a railway having rails the combination of a track magnet disposed transversely of the rails and positioned with one end adjacent one rail and the other end adjacent the other rail and each end separated from its adjacent rail by non-magnetic material, an electric conducting coil having terminals disposed on the magnet intermediate its ends, a water tight container enclosing the magnet and coil, except adjacent the ends of the magnet in proximity to the rails, terminal strips within the container connected to the terminals of the coil, said container formed with an orifice and filled with an insulating compound except a cavity communicating with the orifice and containing the terminal strips, means for reaching the cavity from without the container and means for connecting the conduit to said orifice.
3. As a track element of an inductive train control system for a railway having rails, the combination of a track magnet disposed transversely of the rails and positioned with one end adjacent one rail and the other end adjacent the other rail and each end separated from its adjacent rail by non-magnetic material, an electric conducting coil having terminals disposed on the magnet intermediate its ends, a water tight container enclosing the magnet and coil, except adjacent the ends of the magnet in proximity to the rails, terminal strips within the container connected to the terminals of the coil, said container formed with an orifice and filled with an insulating compound except a cavity communicating with the orifice and containing the terminal strips, means for reaching the cavity from without the container, means for connecting a conduit to said orifice, and means for resiliently connecting the container to the underside of the rails.
4. As a means for supporting a track magnet adjacent the underside of a rail, the combination of two stirrups spaced apart and attached to the rail and extending downwardly therefrom, and a yoke having two ends one resting in each stirrup, and a spring resting on the yoke and disposed to hold the magnet adjacent the underside of the rail.
5. In combination with a railway track consisting of rails and ties for supporting the same; of an inductive trackway device adjacent said rails and having a predetermined and fixed relation to said rails independent of relative movement of rails and ties for transmitting inductive control influences to a passing railway vehicle comprising, a core of laminated magnetic material terminating in poles, a coil on said core, a housing of non-magnetic material enclosing said core and coil except the pole faces of said core, an opening in said casing having a conduit connected thereto, and wires connected to the ends of said coil and contained in said conduit.
6. An influence communicating element for automatic train control system comprising, a core consisting of a stack of laminæ of magnetic material, clamps surrounding said core at points adjacent to its ends, a coil on said core between said clamps, and a casing of non-magnetic material for housing said core and coil, said casing having openings through which the ends of said core extend.
7. Influence communicating means for automatic train control systems comprising, a core of laminated magnetic material terminating in pole faces, a coil on said core having lead-out wires leading therefrom, a casing of non-magnetic material for housing said core and coil having a compartment associated therewith containing an opening extending into said casing and having a wire conduit extending therefrom, wires in said conduit, and readily detachable wire connecting means in said compartment for connecting said lead-out wires to the wires in said conduit.
8. Influence communicating means for automatic train control systems comprising, a core of laminated magnetic material terminating in extensions having pole faces, a coil on said core, a casing of non-magnetic material for housing said core and having openings through which said extensions project, and means for wholly supporting said casing directly by the rails of a railway track, whereby the space relation between the track rails and said core is permanently fixed.
9. A track magnet, for train control systems, in the general form of an elongated rectangular bar with end portions thereon at substantially right angles to the length of the bar, the bar being made up of alternately long

and short longitudinal laminæ with the end portions made up of alternately short and tall laminæ positioned in contact with the top faces, and end faces, respectively, of the said longitudinal laminæ, and means for rigidly holding all of the laminæ together.

10. For use in train control systems, a track magnet having the general form of a rectangular bar formed with an end at right angles thereto at each end, each end being built up of relatively thin laminæ of relatively large dimensions longitudinally and relatively small dimensions transversely, and other laminae of relatively large dimensions longitudinally and substantially the same dimensions transversely.

In testimony whereof I affix my signature.
OSCAR A. ROSS.
